UNITED STATES PATENT OFFICE

106,113

DESIGN FOR A DRESS ENSEMBLE

Mercedes Hall, New York, N. Y.

Application August 2, 1937, Serial No. 70,799

Term of patent 3½ years

To all whom it may concern:

Be it known that I, Mercedes Hall, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

The rear portion of the jacket unit is trimmed with the sequin and bead embroidery as is shown on the front portion thereof.

The four groups of shirring on the top bodice portion of the dress unit, have a jeweled clip between the groups on either side, as shown.

I claim:

The ornamental design for a dress ensemble, substantially as shown and described.

MERCEDES HALL.
